(57) **CLAIM**

The ornamental design for a lounge chair and towel with matching face apertures, as shown and described.

DESCRIPTION

FIG. 1 is a top plan view of a lounge chair and towel with matching face apertures showing my new design with the towel separated from the chair for clarity;

FIG. 2 is a bottom plan view thereof;

FIG. 3 is a right elevation view thereof, the opposite side being a mirror image of the shown;

FIG. 4 is a front elevation view thereof, the opposite end being a mirror image of the shown; and,

FIG. 5 is an isometric view thereof.
